Hello L. ChurchInventor,
Allen E. Ostrander.
By Bakewell, Cornwall Atty's.

UNITED STATES PATENT OFFICE.

ALLEN E. OSTRANDER, OF PATERSON, NEW JERSEY, ASSIGNOR TO AMERICAN CAR & FOUNDRY COMPANY, OF ST. LOUIS, MISSOURI, A CORPORATION OF NEW JERSEY.

CAR CONSTRUCTION.

No. 861,313.

Specification of Letters Patent.

Patented July 30, 1907.

Application filed March 21, 1907. Serial No. 363,621.

To all whom it may concern:

Be it known that I, ALLEN E. OSTRANDER, a citizen of the United States, residing at Paterson, New Jersey, have invented a certain new and useful Improvement 5 in Car Construction, of which the following is a full, clear, and exact description, such as will enable others skilled in the art to which it appertains to make and use the same, reference being had to the accompanying drawings, forming part of this specification, in 10 which—

Figure 1 is a top plan view of a center sill construction embodying the features of my invention; Fig. 2 is a side elevation of one of the sills shown in Fig. 1; Fig. 3 is a cross sectional view taken on the line 3—3 15 of Fig. 2; and Fig. 4 is a cross sectional view taken on the line 4—4 of Fig. 2.

This invention relates to the construction of railway rolling stock.

The object of my invention is to provide a longitudinal sill construction such as is used in the under-frame of a car, which can be manufactured at a low cost, and which will be light, rigid, and capable of carrying great loads.

I have herein illustrated a center sill construction 25 embodying the features of my invention, and referring to the drawings, 1 designates the webs of the sill members, each of these webs being formed from pressed metal and provided at its upper edge with an integral flange 2 that projects outwardly. Secured to the lower 30 edge of each web 1 are two angles 3 that project in opposite directions, the webs 1 being riveted between the vertical legs of said angles, as shown in Fig. 4. Preferably, the lower edges of the webs 1 are sheared off to provide a sill of the fish-bellied type which is 35 of greatest depth at the transverse center of the car, as shown in Fig. 2. The top cover plate 4 is secured to the integral flange 2 at the upper edges of the webs 1, and fastened to the ends of the center sill members at a point intermediate the body bolster 5 and end sill 6, 40 are draft sills 7 which are preferably channel shaped and formed with webs having laterally projecting angles along their lower edge portions and having commercially rolled angles secured along their upper edge portions with the flanges projecting outwardly. These 45 draft sills are connected to the center sills by means of splice plates 8 that are secured to the inside faces of the webs 1 of the center sills, as shown in Fig. 3.

The center sill webs are formed from pressed steel, and the angles 3 secured to the lower portion of said

webs are commercially rolled members so that the sill 50 can be constructed at a low cost and will also be light and of sufficient rigidity to withstand the strains to which it is subjected. Although I have herein shown the inner angles 3 as extending the entire length of the center sill webs it should be understood that my invention is not limited to this exact construction, and if desired said angles may terminate at any convenient point between the deep part of the sill and the part 55 near the bolsters.

Having thus described my invention, what I claim 60 as new and desire to secure by Letters Patent is:

1. A longitudinal car sill consisting of a pressed metal web plate provided at its upper edge with an integral flange, and commercially rolled members secured to the lower edge of said plate; substantially as described. 65

2. A longitudinal car sill consisting of a pressed metal web plate of greatest depth at its center and provided at its upper edge with an integral laterally projecting flange, and commercially rolled members secured to the lower edge of said web plate throughout its entire length; substantially as described. 70

3. A longitudinal car sill consisting of a pressed metal web plate provided at its upper edge with an integral laterally projecting flange, and L-shaped members secured to the lower edge portion of said web plate, said plate being 75 interposed between the vertical legs or flanges of said members; substantially as described.

4. A center sill for a car consisting of a pressed metal web plate that extends from bolster to bolster of the car and having an integral flange at its upper edge, the lower edge of said web plate being sheared off so that said plate gradually diminishes in depth from its middle portion toward its opposite ends, and commercially rolled angles secured to the lower edge of said plate and having their horizontal legs projecting in opposite directions; substantially 80 as described. 85

5. In a center sill construction, pressed metal web plates extending from bolster to bolster of the car and having integral oppositely projecting flanges at their upper edges, commercially rolled angles secured near the lower edges of 90 said plates, with the horizontal legs of said angles projecting in opposite directions, and channel shaped draft sills.

6. In a center sill construction, pressed metal web plates extending from bolster to bolster, said web plates having oppositely projecting integral flanges, angles secured near the lower edges of said web plates and draft sills connected with the end portions of said web plates, said draft sills comprising channel shaped members formed with webs, each having an integral flange and an angle secured to each of said webs near the top edge thereof. 95

7. In combination, a center sill consisting of a pressed metal web plate deepest at its middle portion and having an integral flange at its upper side and a commercially rolled angle secured along its lower edge, and a draft sill secured to said center sill, said draft sill consisting of a 100 web portion with one integral flange and a commercially

105

rolled angle, forming a second flange, secured to said draft sill.

8. In a sill construction, center sills formed of flanged pressed metal web plates deeper at their middle portions than near the ends, commercially rolled angles secured along the lower edge portions of said web plates and channel shaped draft sills connected with the end portions of said center sills, said draft sills comprising flanged web plates with rolled angles secured thereto, with the horizon-

tal legs of the angles and the flanges on the web plates projecting outwardly.

In testimony whereof I hereunto affix my signature in the presence of two witnesses, this 12th day of March 1907.

ALLEN E. OSTRANDER.
